DESIGN FOR A CHIME SIGNAL

Lloyd Rittenhouse, Honeoye Falls, and Frederic S. Grover, Rochester, N. Y., assignors to The A. E. Rittenhouse Co., Inc., Honeoye Falls, N. Y., a corporation of New York

Application August 20, 1941, Serial No. 102,969

Term of patent 7 years

To all whom it may concern:

Be it known that we, Lloyd Rittenhouse and Frederic S. Grover, both citizens of the United States of America and residing at Honeoye Falls and Rochester, respectively, in the county of Monroe and State of New York, have invented a new, original, and ornamental Design for a Chime Signal, of which the following is a specification, reference being had to the accompanying drawing, forming a part thereof.

In the drawing:

Fig. 1 is a front elevation of a chime signal showing our new design;

Fig. 2 is a side elevation of the same, and

Fig. 3 is a top plan view of the same.

We claim:

The ornamental design for a chime signal, as shown.

LLOYD RITTENHOUSE.
FREDERIC S. GROVER.
